UNITED STATES PATENT OFFICE.

DAVID FORBES KEITH, OF TORONTO, ONTARIO, CANADA, ASSIGNOR TO KEITHS
LIMITED, OF TORONTO, CANADA, A CORPORATION OF ONTARIO.

REFRIGERATING APPARATUS.

Application filed January 19, 1921. Serial No. 438,389.

To all whom it may concern:

Be it known that I, DAVID FORBES KEITH, a subject of the King of Great Britain, residing at Toronto, in the county of York and Province of Ontario, Canada, have invented certain new and useful Improvements in Refrigerating Apparatus, of which the following is a specification.

This invention relates to refrigerating apparatus and more particularly to refrigerating apparatus of the intermittent-absorption type in which a refrigerant solution contained within a generator-absorber tank is heated to generate refrigerant gas which passes through a circulation system to a condenser-evaporator tank where the refrigerant is liquefied owing to the pressure and to the application of cooling means operating on the condenser. When a predetermined amount of liquid refrigerant has accumulated in the condenser-evaporator the application of heat to the generator-absorber ceases and the resulting decrease of pressure evaporates the liquid refrigerant accumulated in the condenser-evaporator, the latent heat of vaporization being abstracted from the surrounding air contained within a cold or storage-chamber, which is further chilled in consequence, while the vapor passes back and becomes again absorbed by the liquid within the generator-absorber.

The principal object of the invention is to provide a simple, compact refrigerating apparatus which may be constructed in small units suitable for use, for example, in the home, is entirely automatic in operation, and in which heat is directly removed from the cold or storage-chamber by the air-circulation set up by the vaporization of the refrigerant contained within the condenser-evaporator situated within said chamber.

Another object of the invention is to provide, in a refrigerating apparatus having a circulation system for the refrigerant, a gravity-operated mercury valve to alternately open and close a portion of said system to control the circulation therein.

A further object of the invention is to provide positive means for returning to the

generator-absorber any absorbent liquid which has for any reason accumulated in any other part of the apparatus.

Still another object of the invention is to provide a refrigerating apparatus of the type described, in which the starting of the generation of refrigerant gas is controlled by the temperature of the cold or storage-chamber.

A further object is to provide in a refrigerating apparatus completely housed within a cabinet containing the cold chamber, an arrangement of parts which reduces to a minimum the passage of heat into said cold chamber.

A further object is to provide in a refrigerating apparatus of the type described positive means for preventing a dangerous increase of pressure within the system in case the means for discontinuing the application of heat to the generator-absorber do not operate to discontinue such heating at the proper time.

Other objects will be pointed out as the description progresses.

In the present embodiment of the invention there is provided a refrigerating apparatus of the intermittent-absorption type, comprising a generator-absorber and a condenser-evaporator mounted on opposite arms of a rocking-frame which passes through an aperture in the heat-insulating wall of a cold or storage-chamber, the condenser-evaporator being located within said chamber, means actuated in response to the rocking of said frame in one direction for allowing the refrigerating cycle of operation to proceed, and means controlled by the temperature of said cold or storage-chamber for preventing such movement of said frame while said temperature is below a predetermined figure.

In the drawings illustrating one embodiment of the invention:

Figure 1 is a diagrammatic front elevation, showing the position of the apparatus during the generation of the refrigerant gas;

Fig. 2 is a front sectional elevation, with

certain parts broken away, of the refrigerating apparatus in the position occupied during the absorption of the refrigerant gas;

Fig. 3 is a sectional plan view taken on the line 3—3 of Figure 2; and

Fig. 4 is a sectional end view taken on the line 4—4 of Fig. 2.

In the drawings, 1 designates the outside wall of a cabinet which is divided by the 10 walls 2, of heat-insulating material, into a cold or storage-chamber 3 and an apparatus-chamber 4. The floor of the apparatus-chamber is covered by a metallic drip-pan 5 provided on the three outer sides with a low 15 vertical wall 6, and on the side adjacent the storage-chamber with a higher extension 7 having two marginal flanges which support the moving parts of the refrigerating apparatus.

20 Supported by the front and rear marginal flanges aforesaid is a shaft 8, on which are pivotally mounted one or more supporting-brackets 9, of which two are employed in the present embodiment. Suitably secured to the outer ends of the brackets 9 is a generator-absorber 10, here shown as a drum. A flanged conduit 11 is secured at one end to the drum 10 and forms one arm of a rocking-frame, the other arm of which 25 comprises a similar flanged conduit 12 which supports condenser-evaporator 13. The adjacent flanged ends 14 and 15 of the two conduits (constituting the arms of the rocking-frame) are separated by a disk 16, 30 of fibre or other suitable heat-insulating material, and are held together as by bolts 17, which are insulated from the flange 14 by washers 18 of suitable heat-insulating material, thus obviating any metallic contact between the two arms of the frame, and thereby minimizing the conduction of heat along said frame. The lowering of the generator-absorber 10, by the rocking movement of the frame, is limited by the abutment of 35 a bracket 19, carried by said generator-absorber, against an upward extension 20 of the upright flange 6 of the drip-pan 5; and the rocking movement in the opposite direction (to raise the generator-absorber and lower the condenser-evaporator) is limited by the abutment of the fibre disk 16 against an annular shoulder 21 provided on the extension 7. When the frame is in this latter 40 position, the disk 16 closes the aperture between the apparatus-chamber and the storage-chamber (occupied by the conduit 12), so that heat can pass but slowly therebetween.

45 The condenser-evaporator, while essentially but a closed container, most desirably takes the form of a number of horizontally disposed tubes 22, closed at their inner ends, and supported by the flanged portions 23 of the arm 12 of the rocking-frame. These 50 tubes are covered by a fluted cover 24 of

suitable heat-conducting material. The outer ends of the tubes 22 discharge into a closed header 25, the sloping bottom 26 of which allows any liquid within the header to flow to the end of the return pipe 27.

55 Referring now to the water-circulation system, a trough 29, separated into two compartments by a vertical partition 30, is supported by pipes 31 and 37 to move with the rocking-frame. A constant stream of cooling water is supplied from any suitable exterior supply of water through the fixed pipe 28, which stream discharges into either the right or left-hand compartment of the trough 29 in accordance with the position 60 into which the trough has been shifted by its supporting frame.

65 During the generation of refrigerant vapor when the apparatus is in the position shown in Fig. 1, water flows from the pipe 28 into the right-hand compartment of the trough 29 through pipe 31 to the transverse pipe 32, which is provided with perforations 47 through which the water is discharged upon the cover 24, and flows down the length 70 of the cover in channels between the corrugations which cover the condensing tubes 22, and over the edge 33 into the collecting trough 34. The trough 34 is cut away at a 75 convenient point to allow the water to flow 80 into the drain-conduit 35 from the lower end of which it flows through the pipe 36 into the pan 5. The pan 5 is provided with a 85 suitable discharge-drain, not shown.

90 When the apparatus is in the position 95 shown in Fig. 2, water flows from the pipe 28 into the left-hand compartment of the trough 29 and through the pipe 37 into a water jacket 38 surrounding the lower portion 100 of the generator-absorber 10 from 105 which it passes through the pipe 39 into the pan 5 to be discharged as just described.

110 Reference is now made to the heat-supplying system. The generator-absorber 10 is provided with an electric stove of any known or suitable type. It is preferably placed inside the container, is bodily movable therewith and may be supplied with electric power through the terminals 40 at the front end of the tank 10 which are bent 115 downwardly so as to enter freely into the openings in the top of the cups 41. The cups 41 are supported on a block 42, of suitable insulating material, which is secured to the flange 43 of the wall 6 of the drip-pan. Two conductors 44 connected to a suitable source of electrical power, not shown, may be connected to the cups 41, as by binding screws 45. When the tank 10 is in its lowermost position (as in Fig. 1) 120 the ends of the terminals 40 enter the mercury 46 in the cups 41, thereby closing the circuit of the electric stove to heat the solution contained within the tank. When the 125 apparatus is in the position shown in Fig. 130

2, however, the terminals 40 are removed from the mercury 46 and the circuit of the stove is broken.

In the process of refrigeration, the solution of aqua-ammonia within the generator-absorber is heated, to generate refrigerant ammonia vapor which is conducted to the condenser-evaporator where it is cooled and condensed. The contents of the generator-absorber are then cooled, causing decreased pressure, so that the refrigerant liquid in the condenser-evaporator is evaporated and passes back to the generator-absorber where it is absorbed in the solution therein contained.

Since the gas generated within the generator-absorber is lighter than the solution and rises; an exhaust pipe 52 is connected near the top of the tank 10 to carry off the generated vapor. To effect efficient absorption of the returning vapor, however, it must be introduced below the level of the solution, which would not occur if it were allowed to return through the exhaust pipe 52. There is therefore provided an absorption pipe 57 which terminates below the level of the liquid within the absorber 10, so that returning vapor bubbles up through the liquid and is absorbed.

Means must therefore be supplied to allow vapor to pass freely from the exhaust pipe 52 to the condenser-evaporator, but to prevent returning vapor from passing through said pipe. In previously known refrigerating apparatus of the intermittent-absorption type various mechanical valves have been employed, but without satisfactorily solving the problem. A trap filled with liquid to a definite height, through which the exhaust vapor bubbles on its way to the condenser has also been employed, but this arrangement has many disadvantages, such as causing surging of the trap liquid into the condenser pipe.

There is therefore provided by this invention a trap 48, mounted to rock with the containers carried by the rocking frame, and filled to a suitable level (as shown by the dotted lines in Figs. 1 and 2) with mercury or any suitable heavy liquid having a high boiling point and unattacked by boiling refrigerant. Thus while the apparatus is in the position shown in Fig. 1 refrigerant vapor passes freely from exhaust pipe 52 through trap 48 into rectifying pipe 53 which leads to the condenser. When, however, the apparatus has rocked to the position shown in Fig. 2, the end of exhaust pipe 52 in trap 48 is sealed by the liquid therein, so that refrigerant vapor returning through pipe 53 cannot enter pipe 52 but must pass through absorption pipe 57 to be re-absorbed.

The remainder of the structure will be described in connection with the operation

of the refrigerating apparatus, which is as follows: through the port 49 the apparatus is first exhausted of air, and the generator-absorber 10 is then filled about two-thirds full with a strong solution of aqua-ammonia or other suitable refrigerant, and the trap 48 is partly filled with a suitable liquid (having a high boiling point) to about the level indicated by the dotted lines in Figures 1 and 2, and port 49 is then sealed. While any heavy liquid which will not combine with boiling ammonia may be used in the trap, the best results have been obtained by the employment of mercury. Upon the connection of the conductors 44 to a source of electric power, the apparatus being in the position indicated in Fig. 1, the cycle of operations begins. With the ammonia solution in the generator-absorber 10, that side (the left-hand side) of the apparatus is heavier than the other (right-hand), so that the bracket 19 rests on the side-wall 20, as seen in Figure 1, in which position the circuit for the stove within the generator is complete and heating of the solution begins. As the temperature is raised, ammonia is vaporized from the solution in the generator-absorber, and passes through perforations 50 in the baffle-plate 51, through the exhaust pipe 52 into the trap 48 and thence through the rectifying pipe 53 (which is jacketed, as has been described, by the water pipe 35) into the distributing pipe 54, through the transverse pipe 55 and its vertical branches 56, whence the ammonia vapor is discharged into the tubes 22. Owing to the gradually increasing pressure in the tubes 22 and the flow of cooling water from the pipe 32, the ammonia gas is gradually cooled and liquefied.

While the baffle-plate 51 prevents surging of the solution into the exhaust pipe 52, some water-vapor will, nevertheless, be carried with the generated ammonia vapor, but a large part of this water-vapor will be condensed while passing through the rectifying pipe 53 and will flow back into the generator by gravity through the return pipe 57.

As the generation of ammonia progresses, the weight of the generator (or left-hand) side of the system is decreased and the condensed refrigerant in the tubes 22 gradually increases the weight of the other (or right-hand) side of the system, until at the time that substantially all the ammonia has been driven off from the solution in the generator the shifting of the weight is sufficient to rock the frame to lower the condenser-evaporator and raise the generator-absorber until the disk 16 engages (and rests against) its seat 21.

The condensate which is accumulated in the condenser fills the lower left end of the same. As this end is closed, the condensate is unable to return by gravity to

the generator. From the configuration of the parts, it will be noted that most of the condensate is accumulated so as to have a short moment arm. It is only after considerable condensate has been accumulated and when the added increments are deposited at a considerable distance from the pivot, that the condenser side may be automatically lowered.

10 The apparatus is now in the position shown in Fig. 2. The cover 24 of the condenser-evaporator is now horizontal so that the cooling water trapped in the pipe 31 drips over the right-hand edge of the cover, 15 down the face of the header 25 and over the sloping bottom 58 into the collector 59. A portion of this water runs down a depending stud 60, carried by the condenser-evaporator, so as to fill a suitably-supported stationary cup 61. The collector 59 is drained through the tube 62 which exhausts through 20 the trap 63 into the drip-pan 5.

The cooling water, now flows through the pipe 37 and fills the water jacket 38 around the generator-absorber 10. The addition of this cooling water does not, however, rock the frame, as the condensate is now in a more remote part of the condenser-evaporator and has a longer moment arm sufficient 30 to maintain the rocking frame in the evaporating position. The cooling water in the jacket lowers the temperature and consequently the pressure within the drum, thereby causing the liquid refrigerant in the tubes 35 22 and the header 25 to again vaporize and pass back, through the distributing pipe 54, into the rectifying pipe 53, and then it passes through the absorbing pipe 57, the open end of which is submerged in the solution in 40 the generator-absorber 10, where the ammonia vapor is again absorbed.

As it is desired that the returning refrigerant shall be absorbed in the solution, it is necessary to prevent any vapor from 45 flowing through the trap 48 and the pipe 52. Such flow is effectively prevented by the liquid in the trap 48 which seals the open end of the pipe 52 when the apparatus is in this position.

50 The evaporation of the refrigerant within the condenser-evaporator absorbs heat which can only be supplied from within the storage-chamber 3. The air immediately surrounding the condenser-evaporator thus 55 becomes very cold and, owing to its increased density, passes downwardly through the aperture in the bottom 58, around the collector 59 and through the central aperture in the baffle 64 to the upper portion of the 60 chamber 3. The warm air from near the insulating walls 2 passes upward, preferably through a conduit provided by partition 65, which extends from near the top of the insulated chamber down into the storage compartment 3, and being cooled by contact with

the evaporator descends, as just described. Thus the entire contents of the cold chamber 3 are cooled by convection. In order to increase the conducting surface of the evaporator, depending fins 66 may be carried by 70 the tubes 22. The bottom 58, collector 59, and baffle 64 are most desirably made of heat-insulating material, such as fibre-board or the like so that the heat given off during 75 the condensing of the refrigerant will not be radiated to the chamber 3, but will be carried off by the cooling water flowing through the outlet pipe 35.

As the air circulates about in the refrigerator, moisture is condensed by and frozen 80 onto the cold evaporator thereby drying the entire contents of the refrigerating chamber. This frost which is collected on the evaporator is melted off during the condensation stage and it drains down into the collector 85 59 and thence is discharged from the refrigerator. In each succeeding cycle in the operation of the refrigerator more of the moisture is condensed out thereby maintaining 90 the dry condition in the refrigerator.

When the temperature of the water in the cup 61 is sufficiently lowered by the evaporation of refrigerant within the evaporator, the contents of the cup freezes, thereby locking the stud 60 within the cup 61, which is 95 rigidly secured to the bottom 58 in any desired manner. Thus, although the weight of the left-hand side of the apparatus becomes greater than that of the right-hand side, and tends to rock the supporting-frame 100 to raise the condenser-evaporator (so as to again commence the heating operation), such movement will be prevented until sufficient external heat has leaked into the storage-chamber to melt the ice in the cup 61, thereby releasing the stud 60 and permitting 105 the apparatus to rock back to its original position, as shown in Fig. 1.

Upon the occurrence of this movement 110 there may remain in the condenser-evaporator a small amount of liquid, consisting of condensed water-vapor from the generator-absorber mixed with liquid ammonia; but such liquid, when present, will be in the lower corner of the header 25, whence it will 115 flow by gravity through the return pipe 27, and the pipes 54 and 57, back into the lower part of the generator-absorber.

It will be noted that in Fig. 2 the pipe 120 27 slopes upwardly toward the left, and hence liquid cannot return by gravity from the header 25 to the generator-absorber. As the pipe 27 leads into pipe 54 which is full of gas, there can be no syphoning of the liquid through the pipe 27. The point of connection of the pipes 27 and 54 is, it will 125 be noted, approximately directly over the pivot 8; hence, as the frame rocks, the elevation of this point does not appreciably change. When, however, the apparatus is 130

in the position shown in Fig. 1, the pipe 27 slopes downwardly to the left, and hence liquid can drain by gravity.

During the condensation stage the condenser-evaporator is operating at a comparatively high temperature. This high temperature, for satisfactory and economical operation of the refrigerator, should not be permitted to affect the temperature of the lower part of the chamber where the food is stored. This is brought about in the present construction by the partition 65 which, as shown in Figs. 2 and 4, extends from near the top of the thermally-insulated chamber to well below the condenser-evaporator, the ice lock and baffles. The hot air which surrounds the condenser-evaporator in the condensing stage rises to the top of the chamber and stays there excepting the small quantity leaking out through the aperture. It is impossible for convection currents to be set up between the lower part of the storage chamber and the top of the partition 65. This follows from the fact that the hot air in the chamber is unable to drop down and mix with the cold air. Hence, the hot condenser has no appreciable effect on the temperature of the storage chamber, neither does it vaporize the water extracted by the cold evaporator. On the lowering of the condenser-evaporator and the chilling of the surroundings upon the evaporation of the refrigerant, the cold air is able to drop down from the condenser-evaporator and set up the air currents indicated in Figs. 2, 3 and 4.

If for any reason during the heating of the solution in the generator-absorber the condensing-tubes 22 should become filled too full of liquid refrigerant (so as to tend to cause a dangerously high pressure within the system), the refrigerant liquid would overflow from the upper end of the tubes 22 into the header 25, whence it would flow, as just described, back into the generator-absorber. 10. As additional vapor is generated in the generator-absorber and passes into the condenser-evaporator to be liquefied, an equivalent amount of the liquid overflows into the header and flows back (as before) into the lower part of the generator-absorber. So that a condition of equilibrium would soon be reached, under which a stream of vapor leaves the top of the generator-absorber, while its place is being constantly supplied by an equivalent stream of liquid flowing back into the bottom of said generator-absorber. Inasmuch as high pressure will attend the filling of the condenser-evaporator with liquid, this arrangement places a definite limit to the high pressure.

While the preferred embodiment of the invention has been described with great detail, it is to be understood that this is for the sake of clearness only, and does not limit

the scope of the invention as defined by the annexed claims.

The invention having been thus fully described, what is claimed is:

1. A refrigerating apparatus of the intermittent absorption type, comprising a rocking frame carrying upon its opposite arms two containers, the one a generator-absorber and the other a condenser-evaporator, and means associated with the containers and frame whereby a refrigerating cycle may be performed, said means including a casing moving with said frame and having an inlet and an outlet, and containing enough mercury to seal said outlet in one position only of said frame and casing while leaving it free in the other position, the mouth of said inlet being at all times above the level of the mercury.

2. A refrigerating apparatus of the intermittent absorption type, comprising a rocking frame carrying upon its opposite arms two containers, the one a generator-absorber and the other a condenser-evaporator, and means associated with the containers and frame whereby a refrigerating cycle may be performed, said means including an approximately horizontal casing carried by the rocking-frame and elongated in a direction transverse to the pivot of the frame, an outlet-pipe passing through the roof of the casing to the condenser-absorber and having its mouth located within the casing in proximity to its floor and nearer that end thereof which becomes the relatively lower end when

the frame has been rocked into absorption-position, an inlet-pipe passing from the generator-absorber through the floor of said casing and having its mouth located within the casing substantially above said floor, and within said casing a body of mercury whose level is always below said inlet-mouth in either position of the rocking-frame and casing, said body of mercury being enough to seal said outlet-mouth so long only as the absorber is in its elevated absorption-position with said outlet-mouth relatively lowered, said mercury leaving said outlet-mouth free in the other position.

3. In a refrigerating apparatus of the intermittent absorption type, the combination with a rocking-frame, of a generator-absorber on one arm thereof and a condenser-evaporator on the other arm thereof, a casing between and connecting said generator-absorber and condenser-evaporator and moving with said frame, said casing having an inlet and outlet projecting therein and containing sufficient fluid to seal the outlet in one position of the frame while leaving it free in the other position, the mouth of the inlet being at all times free of and above the level of the fluid in the casing.

4. In a refrigerating apparatus of the in-

termittent absorption type, the combination with a rocking-frame, of a generator-absorber and condenser-evaporator at opposite ends thereof, a casing having fluid therein and moving with said frame, said casing being interposed between said generator-absorber and condenser-evaporator, conduits extending from said generator-absorber and

condenser-evaporator and terminating in said casing, one of said conduits being immersed in the fluid in one position of the frame and free of said fluid in the other position, and the other conduit being at all times free of and above the level of the fluid in the casing.

DAVID FORBES KEITH.
